UNITED STATES PATENT OFFICE

151,037

DESIGN FOR A LAMP

Joseph Frank, Forest Hills, and Sidney R. Geist,
New York, N. Y., assignors to Gemloid Corporation,
Elmhurst, Long Island, N. Y., a corporation of New York

Application April 19, 1946, Serial No. 128,791

Term of patent 3½ years

(Cl. D48—20)

To all whom it may concern:

Be it known that we, Joseph Frank and Sidney R. Geist, citizens of the United States, residing at Forest Hills, in the county of Queens and State of New York, and New York, in the county of New York and State of New York, respectively, have invented a new, original, and ornamental Design for a Lamp, of which the following is a specification, reference being had to the accompanying drawing, forming part thereof.

We claim:

The ornamental design for a lamp, substantially as shown.

JOSEPH FRANK.
SIDNEY R. GEIST.
